Nat Lipton, Long Beach, Calif.

Application October 22, 1947, Serial No. 142,089

Term of patent 14 years

(Cl. D4—3)

To all whom it may concern:

Be it known that I, Nat Lipton, a citizen of the United States, residing at 2327 Pine Avenue, in the city of Long Beach 6, in the county of Los Angeles and State of California, have invented a new, original, and ornamental Design for combined Tooth Paste Dispenser and Toothbrush Holder, of which the following is a specification, reference being had to the accompanying drawings, forming part thereof.

Figure 1 is a perspective view; Figure 2 is a top plan view; Figure 3 is a right side elevation; and Figure 4 is a rear view of a combined tooth paste dispenser and toothbrush holder, showing my new design.

I claim:

The ornamental design for a combined tooth paste dispenser and toothbrush holder, as shown.
NAT LIPTON.
